SOUTH AUSTRALIA, AUSTRALIA

DEVICE FOR PUMPING FLUIDS

Application filed November 20, 1928, Serial No. 320,616, and in Australia November 26, 1927.

This invention comprises a device for removing water, air or other fluid from a receptacle. In particular it has been devised for removing water or other liquid from a boat 5 or the like, being applicable to boats propelled by any means.

Our device comprises as its essential features a tube having at or towards one end—the inlet end—an inlet valve and at or towards its other end—the outlet end—an outlet valve, and having intermediate its ends one or more comparatively large resilient bulbs by the alternate compression and expansion of which gases, water or other liquid 15 may be forced through the tube. We may also provide a supplementary or by-pass tube passing around the main bulb or container and fitted with a supplementary bulb and valves whereby the main tube and bulb or 20 container may be primed with fluid or the fluid may be exhausted therefrom.

In order that our invention may be the more clearly understood we will describe the same with reference to the accompanying 25 drawings which are more or less diagrammatic and in which

Fig. 1 is a sectional side view showing our invention fitted to a boat.

Fig. 2 is a plan view of our invention in its 30 simplest form.

Fig. 3 is a section on line 3 3 of Fig. 2, showing a spring device for supplementing the action of the resilient bulb.

Fig. 4 is a plan view of a larger unit fitted 35 with a supplementary by-pass tube fitted for priming and for evacuating the main tube and bulb or container.

The several parts of our device are preferably of such size and so proportioned that the resilient bulb or container 1 may be fastened upon the seat of the boat or upon the floor of same with the inlet end 2 of the tube upon the bottom and submerged in any water that may be within the boat and with the outlet end 3 of the tube over the side of same. Or the outlet end may be passed through a suitable opening in the side or the bottom of the boat. The inlet portion of the tube is fitted with an inlet valve 4 and the outlet portion of the tube is fitted with an outlet

valve 5. One or more of the occupants of the boat by sitting or standing upon the bulb or container 1, as he or they sway from side to side or otherwise move upon them will cause the bulb or bulbs or containers to be alternately compressed and expanded and water that may be in the bottom of the boat is drawn through the tube and forced overboard. The bulb or bulbs are preferably held between top and bottom boards or gratings. Or the bulb or bulbs may be otherwise fixed where they are subject to alternate compression and expansion by the motion of the occupants of the boat or otherwise. When several bulbs are used additional valves may be provided between them to prevent back flow.

The tube 2 and 3 is made preferably of rubber or canvas, and the bulbs 1 may be made of rubber or other resilient material and may be provided with internal springs or other means to supplement the expanding action of the rubber or other resilient material if so desired. In Fig. 3 we have shown a spring device comprising two crossed rings 6 connected by supplementary spiral springs. The bulbs 75 are preferably covered with net or other means to prevent undue distortion of any part of same. This however is not shown in the drawings.

According to a modification of our device 80 we may provide it with a supplementary by-pass tube 16 as shown in Fig. 4 wherein the resilient main bulb or container 1 is represented as made in the form of a hollow ring containing a number of enclosed independent 85 bulbs or tubes to provide greater resiliency, each of such bulbs or tubes having perforations whereby water may enter and be expelled. 4 and 5 represent the inlet and outlet valves as in the original device. The tube 16 is provided with a supplementary bulb 17 and with additional inlet and outlet valves 18 and 19 respectively. The inlet tube 2 is provided with a supplementary bulb 20 and a second valve 21. Cocks 22, 23 and 24 are 90 provided in the several tubes. By these means the main bulb or container may be primed with water or the water may be exhausted from same thereby rendering it suitable for use as a life belt, raft or apparatus 95 100

to raise a boat if sunk. In order to prime the main bulb 1 the cock 22 is closed and cocks 23 and 24 are opened; by operating the supplementary bulb 20 water is forced from the bottom of the boat through the main tube and main bulb expelling the air therefrom and filling them with water; all cocks are now opened, and the main bulb is ready for operation as previously described to discharge the water from the boat. If it should be desired to discontinue to discharge the water from the boat and to exhaust the water from the main bulb the bulb 17 is operated, pressure being maintained upon the main bulb.

For the purpose of emptying water from a boat pulled up on to a ramp or platform the simple form of our invention shown in Fig. 2 may be employed either for pumping continuously or merely to start and carry on siphonage, for which latter purpose two or three compressions of the bulb will suffice.

What we claim is:—

A device of the character described comprising a resilient tube having confined therein a plurality of large resilient perforated bulbs, an inlet tube connected to said first mentioned tube and provided with a supplementary bulb, a valve disposed upon opposite sides of said supplementary bulb, a cock in said inlet tube disposed between one of said valves and said first named tube, an outlet tube connected to said first named tube having a valve, a cock between said valve and said first named tube, and a by-pass tube connected to said inlet tube between said cock and valve of the supplementary bulb, said by-pass tube being connected to said outlet tube in advance of the valve thereof; a cock in said by-pass tube, a valve in said tube between said cock and said inlet, a bulb disposed in said by-pass and positioned between said cock and said outlet, and a valve between said bulb and outlet, whereby the closing of the cock in the by-pass and opening the cocks in the inlet and outlet tubes enables the device to be used as a pump by alternate compression and expansion of said first named tube, and whereby the closing of the cocks in the inlet and outlet pipes and opening of the cock in the by-pass, enables it to be used as a siphon once the fluid has been set in motion.

In testimony that we claim the foregoing as our invention we have signed our names

65 this twelfth day of October, 1928.

JOHN ROBB MUIRHEAD.
JOHN WILLIAM MILLS.
